UNITED STATES PATENT OFFICE.

ALFRED P. CRANSTON, OF NEW YORK, N. Y.

VACUUM-CLEANER HANDLE.

No. 873,300.

Specification of Letters Patent.

Patented Dec. 10, 1907.

Application filed May 7 1907. Serial No. 372,347.

To all whom it may concern:

Be it known that I, ALFRED P. CRANSTON, a citizen of the United States, residing in the city of New York, borough of Manhattan, county and State of New York, have invented certain new and useful Improvements in Vacuum-Cleaner Handles, of which the following is a full, clear, and exact specification.

This invention relates to vacuum cleaner handles.

The improvements of the present invention are particularly adapted for use in connection with that type of vacuum cleaning apparatus, which comprises a pump or suction device, having dust collecting means connected by a flexible hose with a portable handle or a sucker, which is moved over the floor or other surfaces to be cleaned.

Vacuum cleaner handles of the type indicated are usually formed of a light metal pipe having a mouth or suction slot at their lower end and having their upper end curved or bent to receive a flexible hose, which is connected with the pump. It is found in practice, that the upwardly moving stream of dust or grit laden air impinges against the metal pipe, at the curved upper end thereof, and soon wears a hole in the same, thereby destroying the usefulness of the handle and requiring a new handle. Furthermore, it is found in practice, that where a metal handle or pipe of the type indicated is employed, it is difficult to know just when the surface over which the device is moved has been completely cleaned.

With the above premises in view, the object of the present invention is to improve the construction of vacuum cleaner handles, principally in such a manner as to increase the period of their usefulness, by overcoming or avoiding the effects of wear, and also to enable the operator using the vacuum cleaner to inspect the dust laden air passing through the handle, so that he can determine when a surface has been properly cleaned.

With the foregoing and other objects in view, which will appear as the description proceeds, the invention resides in the construction, combination and arrangement of parts and in the details hereinafter described and claimed, it being understood that changes in the precise embodiment of invention herein disclosed can be made within the

scope of the following claims without departing from the spirit of the invention.

In the accompanying drawing forming part of this specification, Figure 1, is a longitudinal section, partly in elevation, through a vacuum cleaner handle constructed in accordance with the invention. Fig. 2, is a detail sectional view, showing a modification. Fig. 3, is a sectional view of another modification. Fig. 4, is a plan view of the construction shown in Fig. 3.

Referring to Fig. 1, the reference letter A indicates in a general manner the curved upper end of a vacuum cleaner handle, and B indicates a flexible pipe or hose, which is suitably connected with the upper end of handle A for conveying the dust laden air to a suitable dust collecting or settling device.

It is found in practice, that the dust or grit carried by the upwardly moving stream of air impinges against the curved upper end of the handle A, so as to wear through the same. For the purpose of materially overcoming this tendency to wear, the curved upper portion 1 of the handle A according to my invention is reinforced in any suitable manner, such as by thickening the same, as illustrated in Fig. 1, whereby the life of the handle is prolonged.

In the embodiment of the invention illustrated in Fig. 1, the handle A is formed of a lower metallic section 2, and an upper section 3, which is detachably connected with the lower section 2 in any suitable manner, such as by means of screw threads as indicated at 4. The upper section 3 is curved as shown in Fig. 3 and is reinforced at 1 as previously described. Furthermore, the upper section 3 preferably is formed of hard transparent material, such for example as glass, the vitreous character of which enables it to withstand the wear of the dust laden air to a great extent. By reason of its transparent character, the operator can watch the column of dust laden air through the section 3, and can thus determine by the absence of dust, when a surface has been properly cleaned. If the section 3 should become worn through long service, it can be readily detached from the lower metallic section 2, and a new section 3 substituted at small expense. In the construction shown in Fig. 1, the section 3, at its upper end is provided with screw threads 5 by means of which it

can be screwed into the end of the flexible hose B.

In the modified construction illustrated in Fig. 2, the glass section 3 is formed with a conical or tapered upper end 7, which is provided with corrugations, and is adapted to be thrust into the end of the hose B, as shown, so as to form a tight joint.

In the modified construction illustrated in Figs. 3 and 4, the curved upper end 8 of the handle is constructed of metal and is formed at the curved portion thereof with a rabbeted opening into which is fitted a glass plate or window 9, which is thickened as shown, and is removably held in place in any suitable manner, such as by means of the catches 10, which are adapted to be rotated upon suitable pivoted pins or screws 11, whereby a new plate 9 can be inserted whenever the old one becomes worn. As the plate 9 preferably is formed of glass or other transparent material, it provides a sighting device to inspect the dust laden air, and also presents a hard surface to receive the wear of the dust or grit.

The improved handle of the present invention is strong, simple, durable and inexpensive in construction, as well as thoroughly efficient in use.

What is claimed is:

1. A vacuum cleaner handle reinforced at the portions of greatest wear.
2. A vacuum cleaner handle having its curved portions reinforced.
3. A vacuum cleaner handle having a detachable sighting device.
4. A vacuum cleaner handle having a curved detachable sighting device.
5. A vacuum cleaner handle having a reinforced transparent portion.
6. A vacuum cleaner handle having a detachable curved reinforced portion.
7. A vacuum cleaner handle comprising a metallic portion and curved transparent portion.
8. A vacuum cleaner handle having a metallic portion and a detachable curved transparent thickened portion, substantially as set forth.

In testimony whereof, I have hereunto set my hand in the presence of two subscribing witnesses.

ALFRED P. CRANSTON.
